UNITED STATES PATENT OFFICE.

ISRAEL WEINSTEIN, OF CHICAGO, ILLINOIS.

ILLUMINATED SIGN.

Application filed November 15, 1924. Serial No. 750,073.

This invention relates to signs and relates particularly to illuminated signs.

The invention seeks to decrease the energy necessary to maintain proper illumination of an electric sign, by means of a novel arrangement of reflectors within the casing of such a sign.

It is also an object of the invention to provide a member simulating an electric light bulb and adapted to be so mounted upon the interiorly illuminated casing of an electric sign as to transmit light through a wall of said casing so that said member will appear to be itself a source of light.

These and various other objects the invention attains by the construction hereinafter described and illustrated in the accompanying drawings, wherein:

Figure 1 is a view, partly in vertical section, of a sign embodying one form of the invention.

Figure 2 is a cross-section view of the same, taken upon the line 2—2 of Figure 1.

Figure 3 is a sectional view on line 3—3 of Figure 1, showing the mounting of two reversely arranged reflector members upon a common support.

Figure 4 is a detail sectional view, taken upon line 4—4 of Figure 1, showing one of the bulb-simulating members.

Figure 5 is a perspective view showing an alternative provision for mounting the reversely arranged reflectors.

Fig. 6 is a cross section view taken upon the line 6—6 of Fig. 1.

Figure 7 is a view similar to Figure 1 but showing an alternative construction.

Fig. 8 is a section on line 8—8 of Fig. 7.

In these views, the reference character 1 designates a casing which, as shown, is formed of sheet metal but may be of any suitable material. The front and back walls of said casing may be provided, as is best seen in Fig. 1, with windows 2 of glass or the like upon which signs may be lettered, or said signs may be produced in some other well known manner. Upon the top and bottom of the casing 1 therewithin rows of electric bulbs 3 (or other light sources) are extended longitudinally of the casing, and midway between the top and bottom, two other rows of lighting elements 4 are mounted in sockets carried by a longitudinally extending conduit 5. In the bottom of the casing and in its end walls and front and back walls, openings 6 are formed to give

access when desired to the various lighting elements, said openings being normally closed by suitable doors 7, hinged as indicated at 8 or otherwise suitably and adjustably secured to the casing.

Between the bulbs 4 and each row of bulbs 3, there is arranged a sheet metal reflector unit 9, 10 having in cross-section the conventional diamond shape, as is best seen in Fig. 2. Thus, each member 9, 10 comprises an upper reflector 9 formed preferably by a single sheet of metal bent to the form of an inverted V and further comprises a lower V-shaped reflector 10. The two said reflectors are rigidly connected, preferably by securing the same to a common support which may extend between said reflectors. Thus the adjacent edges of the reflectors comprising each unit 9, 10 are shown as formed with horizontal flanges 11, which engage in keepers 12 formed by bending toward each other the front and rear edges of two sheet metal plates 13, one superposed on the other and the two being rigidly connected by rivets 14 or other suitable means.

It is preferred to provide means for supporting the two reflector units 9, 10 in common and this same supporting means may also carry the conduit 5, so as to properly position the latter and the lighting elements 4 between the two said units. Thus at each end of said units 9, 10 a pair of spaced metal bars 15 extend vertically, being rigidly secured at their extremities to the top and bottom of the casing, as is indicated at 16. The end portions of the two plates 13 are upwardly and downwardly bent, as is indicated at 17 and are secured by rivets 18 or the like to said vertical bars. Each pair of end bars 15 are connected by a cross bar 19 arranged at a level with the conduit 5 and the ends of said conduit are engaged with fittings 20 which are secured in any suitable manner to the cross bars 19.

In addition to the longitudinally extended reflector units 9, 10, it is preferred to arrange within the casing 1, in the end portions thereof vertically elongated reflectors 21, which are similar in form to the reflectors 9 and 10 but form a horizontal V. The bars 15 which carry the units 9, 10 may also carry the reflectors 21. Thus the diverged margins of each of the latter are flanged toward the front and back of the casing and are riveted or otherwise suitably secured to the outer faces of the bars 15. From said

bars the walls of each reflector 21 converge toward a vertical row of light bulbs 22, there being one such row interiorly mounted upon each end wall of the casing.

5 From the preceding description it will be seen that the four uprights 15 constitutes a support for all of the reflector members as well as for the conduit 5, it being conveniently feasible to assemble said reflector members and said conduit in their proper relation upon said uprights, exteriorly of the casing the completed assembly then being properly positioned within said casing.

10 The light rays emanating from the rows of bulbs 22 will be divided by the adjacent reflectors 21, and will be reflected forwardly and rearwardly by the divergent walls of said reflectors. Similarly the light radiating upwardly and downwardly from the 15 bulbs 3 and 4 will encounter the divergent walls of the reflectors 9 and 10 and will also be reflected forwardly and rearwardly. By thus substantially eliminating any wasteful radiation from the lighting elements, the invention reduces the requisite number of such 20 elements to a minimum.

25 As a further economical feature, the invention provides members, which may be mounted upon the walls of a sign casing, similarly to light bulbs, said members being formed to simulate light bulbs but having no conducting filaments and being adapted for illumination by light rays passing therethrough rather than by the generation of light therewithin. Referring now particularly to Fig. 4, the reference character 23 designates a bulb-shaped member formed of glass or like transparent material, one end thereof being of somewhat reduced diameter and being formed with an unobstructed 30 opening. To said open end there is rigidly secured a tubular base member 24 which is screw-threaded or otherwise adapted for mounting upon some suitable support. Two 35 such supports are provided in the disclosed invention, each consisting of a rectangular frame of bar metal 25, said frames marginally engaging the front and back walls of the casing interiorly of the latter. Each 40 of said frames is formed with suitably spaced threaded openings 26, each preferably in line with one of the bulbs 3, and each of said openings is adapted to receive the threaded base 24 of one of the false light 45 bulbs 23. Thus said bulbs 23 form an ornamental border about the front and rear walls of the sign and are so illuminated by rays from the aligned lighting elements 3 as to produce a simulation of energized light 50 bulbs.

55 Preferably the openings 6 in the vertical walls of the casing are provided not only with the closures 7 but also with sheet metal eaves 27 secured to the casing above said 60 closures projecting sufficiently to prevent

access to said openings of water flowing down said walls during rain.

65 In the alternative construction illustrated in Figure 5, upper and lower inclined reflectors 27 and 28 are engaged with a supporting rod 29, tongues 30 upon said reflectors being rolled to form sleeves adapted to alternately embrace said rod.

70 In that form of the invention which is shown in Figures 7 and 8, rows of lighting 75 elements 31 are mounted within the casing upon its top and bottom and two rows 32 of such elements are carried by a conduit 33 at a level substantially midway between the top and bottom, all as in the construction 80 first described. In the structure now being described, however, the conduit 33 extends the full length of the sign casing, its ends engaging fittings 34 detachably secured to hingedly mounted closures 35 for openings 85 36 in the end walls of the casing. Through either of said openings, the conduit after being detached from the closures 35, may be removed together with its lighting elements 90 32. The illustrated connection between the 95 conduit and said closures is established by studs 37 projecting from the fittings 34 through said closures and engaged exteriorly of the closures by nuts 38.

100 Between the lighting elements 32 and each row of lighting elements 31 there is disposed a reflector unit 39, 40 differing from the units 9, 10 of the first described construction in that it extends the full length of the casing, the plates 41 supporting the 105 unit being upwardly and downwardly bent at their ends as indicated at 42 and suitably secured to the end walls of the casing.

110 It is a feature of both of the described constructions that the reflector members 9 and 10 or 39 and 40 may be very readily assembled upon the plates 13 or 41. That is to say a slight decrease in the angle between the convergent walls of any of said reflector members will permit their marginal longitudinal flanges to be removed from the keepers of the supporting plates 115 13 or 41 and similarly said members may be engaged with said keepers by increasing the divergency of their walls.

What I claim is:

1. In an illuminated sign, a pair of spaced sign elements, two rows of light elements between said sign elements, a pair of reverse- 120 ly arranged V-shaped reflector members extending between and parallel to said rows, each formed from a sheet of metal, the diverged edges of said members being adjacent, and a common support for said members having quick detachable sliding engagement with said edges.

2. In an illuminated sign, a casing, a row of lighting elements in each end portion of the casing parallel to the end walls thereof, a reflector member in each end portion of 130

the casing having reflector faces converging toward the row of lighting elements in said end portion, spaced rows of lighting elements extending lengthwise of the casing, 5 and a reflector member between said spaced rows having reflecting faces converging toward each of said rows, and sign elements carried by said casing between which said lighting elements are disposed.

10 3. In an illuminated sign, a casing, and a unit reflector structure comprising a pair of reflectors adapted to be disposed within the end portions of the casing, spaced reflectors extending longitudinally of the casing, lighting means arranged between said spaced reflectors, a common means for supporting said reflectors within the casing, and sign elements carried by the casing at opposite sides thereof.

15 4. In an illuminated sign, a casing, a pair of uprights mounted in the end portions of said casing, a reflector vertically extended upon each of said uprights, upon its outer side, lighting means operatively disposed with relation to said reflectors, a reflector extended between and carried by said uprights, lighting means co-acting with the last mentioned reflector, and a sign member carried by the casing and jointly illuminated by 20 said lighting means and reflectors.

25 5. In an illuminated sign, a casing, a pair of uprights disposed in the end portions of said casing, a support extending between and mounted upon said uprights, lighting means carried by said support, and a pair of reflectors co-acting with said lighting means, respectively thereabove and therebelow, and extending between and mounted upon said uprights, and a sign member carried by the 30 casing and illuminated by said reflectors and lighting means.

40 6. In an illuminated sign, a casing, a pair of sign members carried by said casing on opposite sides thereof, a row of lighting elements extended lengthwise within said casing, means co-acting with said elements to reflect the light thereof upon both of said

sign members, lighting elements in the end portions of said casing, reflecting means within said end portions co-acting with said lighting means for further illuminating both of said sign members, and supporting means for both of said reflecting means insertable in and removable from said casing as a unit.

45 7. In an illuminated sign, a casing, sign members carried by said casing upon opposite sides thereof, a row of light elements within said casing, reflectors above and below said row of elements parallel therewith and facing both of said sign members, and a common support for said lighting elements and reflectors insertable in and removable from said casing as a unit.

50 8. In an illuminated sign, a casing, a sign member carried by said casing, uprights in the end portions of said casing, light elements and co-acting reflectors in each end portion of said casing, illuminating said sign element, one thereof being mounted upon the upright in each of said ends, connections between said uprights adapting them for removal as a unit, and co-acting lighting elements and reflectors mounted upon said connections and illuminating said 55 sign member.

55 9. In an illuminated sign, a casing, a sign member carried by said casing, a frame in the casing, a light source, and a co-acting reflector in each end of the casing, one thereof in each end being mounted upon the corresponding end of said frame and the other upon said casing, a lighting element, and a co-acting reflector disposed between the ends of the casing, one thereof carried by the casing, and the other by said frame, said frame and said members carried thereby being insertable as a unit into the casing and into proper co-acting relation with said members carried by the casing.

60 90 In testimony whereof I sign this specification.

ISRAEL WEINSTEIN.
